Specification of Letters Patent. Patented May 2, 1922.

Application filed March 31, 1921. Serial No. 457,432.

To all whom it may concern:

Be it known that I, IRVING S. KAUFMAN, a citizen of the United States, residing at Chicago, in the county of Cook and State of Illinois, have invented a certain new and useful Improvement in Cuff Links, of which the following is a full, clear, concise, and exact description, reference being had to the accompanying drawings, forming a part of this specification.

My invention relates to cuff-links and the like.

The object of my invention is the provision of a novel, simple and compact cuff-link which will properly join or connect the edges of the cuff or sleeve of a garment to provide the desired snug fit of the sleeve about the arm and which will at the same time permit enlargement of the sleeve opening without removing or even partially removing the link. Heretofore, where the desired snug fit of the cuff about the arm has been provided, it has been invariably necessary to remove or at least partially remove the cuff-link to permit insertion or withdrawal of the hand through the cuff opening. Likewise, it has heretofore been necessary to remove or at least partially remove the cuff-link to roll up the sleeve of the garment or otherwise move the cuff opening up the forearm to a point where a larger opening would be necessary than at the wrist.

My invention provides a cuff-link comprising a pair of button or head portions or a button portion and a head portion as desired joined by a yieldable shank portion adapted to permit separation of the button or head portion to allow enlargement of the sleeve opening without removing or even partially removing the link as has been necessary heretofore. The enlargement of the cuff opening allowed by the link of my invention permits ready insertion or removal of the hand therethrough or movement of the cuff up the forearm of the wearer. Means between the button or head portions of the link provides for again bringing the edges of the cuff properly together following the enlargement of the sleeve opening such as caused by insertion or withdrawal of the hand therethrough or by movement of the cuff up the forearm of the wearer of the garment. By providing spring means to this end, I find that instead of removing the link and rolling up the cuff as heretofore necessary the cuff may be pulled or drawn up the forearm

and that the sleeve will thereupon be retained in the raised position in which it is arranged by the spring tension tending to return the edges of the cuff to closed position.

A further object of my invention is the provision of a link of this general construction, which will not only be exceedingly simple and compact, but which will be of a pleasing and highly finished appearance.

Other features of my invention will appear from the following detailed description and claims, taken with an inspection of the accompanying drawings, wherein I have illustrated a particular embodiment of the invention.

In the drawings:

Figure 1 is a side elevational view of the two head portions of the link before connecting them together, showing the springs arranged about the shanks thereof. Figure 2 is a longitudinal, sectional view of the sleeve for coupling or connecting the head portions shown in Figure 1 together;

Figure 3 is a side elevational view of the two head portions of the link as connected together, showing the connecting sleeve or coupler in section;

Figure 4 is a side elevational view of the link;

Figure 5 is a perspective view of a cuff showing the edges thereof connected with a link embodying my invention;

Figure 6 is a longitudinal sectional view through an alternative form of connecting sleeve or coupler showing fragmentarily the shanks of the head portions of the link arranged therein;

Figure 7 is a view similar to Figure 4 of a modification; and

Figure 8 is a view similar to Figure 3 of a further modification.

Referring first to Figures 1 to 5, inclusive, of the drawings, the link shown therein comprises a pair of head members 5 and 6 yieldably joined together in a manner which will be more fully set forth as this description proceeds. The head members 5 and 6 each includes a button portion 7 which may be in the nature of the usual flat disk or of any other desired formation. The button portions 7 may be similar or they may be different as desired. One might even be in the form of a button and the other simply a headed end. Shanks 8 connected to the disks or head members 7 of the link through suitable hook and eye connections as shown

at 9 are headed at their free ends as shown at 10. Suitable coiled springs 11 are arranged about each of the shank portions 8 for engagement at one end with the headed 5 ends 10 thereof. The shank portions 8 with the springs 11 arranged thereabout are then arranged in the coupling or connecting sleeve 12 whereupon the opposite ends of the sleeve 12 are turned or rounded in as 10 shown at 13 providing suitable abutments between which abutments and the adjacent or abutting head portions 10 of the shanks 8, the springs 11 are confined.

In use, the button portions 7 of the link 15 are inserted through suitable buttonholes provided adjacent the edges of the cuff 14 as shown at Figure 5 to join or connect the edges of the cuff in the usual manner. The springs 11 normally retain the head portions 20 of the link in substantially the position shown in full lines in Figure 3 providing a snug fit of the sleeve about the arm of the wearer. Where the cuff or sleeve opening 15 is of such size that insertion 25 or withdrawal of the hand through such opening would otherwise be impossible without removing or at least partially removing the link as invariably necessary heretofore, separation of the button portions 30 of my improved link into the positions shown in dotted lines in Figure 3 against the tension of the springs 11 permits adequate enlargement of the opening 15 as indicated in dotted lines at 16 for 35 insertion or withdrawal of the hand, or movement of the cuff up the forearm of the wearer. When the hand has been inserted or withdrawn the springs 11 acting against the headed ends 10 of the shanks 8 40 move the head portions of the link back into the position shown in full lines bringing the edges 17 of the cuffs properly together. Where the cuff is pulled or drawn up the forearm, the tendency of the springs 45 11 to return the head portions of the link to the position shown in full lines provides a tight fit of the cuff about the arm and thereby retains the same in any raised position in which it is arranged.

50 It will now be apparent that I have provided a simple compact and effective yieldable connection between the head members of the link. It should be noted that these provisions are made without in any way impairing the pleasing appearance of the links. In fact, the appearance of the link is enhanced by the yieldable connection I have provided. The formation and assembly of the several parts may be had at a relatively 55 low cost. The springs and headed ends of the shank portions of the link are all compactly housed and operable in the connecting or coupling sleeve 12.

In Figure 6 I have shown another form 65 of yieldable connection between the button

or head portions of the link. In this case, the connecting or coupling sleeve 12' is provided with overlying compartments in which the headed ends of the shank portions 8' are arranged for movement against 70 the tension of springs 11' arranged between the heads 10' and the end walls 13' of the sleeve. This arrangement obviously provides for a relatively greater separation 75 of the button or head portions of the link without increasing the length of the coupling or connecting sleeve 12'.

In Figure 8 I have shown still another form of yieldable connection between the button or head portions of the link. In 80 this case the sleeve 20 is connected to the button portion 21 of the link through a hook and eye or other suitable connection as shown at 22. The shank 23 connected with the button portion 24 through a similar 85 connection 25 is operable in the sleeve 20 against the tension of a suitable coil spring 26 arranged between the headed end 27 of the shank 23 and the end 28 of the sleeve 20.

In Figure 7 I have shown a still further 90 modification. In this case, a tightly coiled and properly finished spring 30 forms the sole connection between the head or button portions 31 of the link. Separation of the button portions 31 is against the tension 95 of the spring 30, the tendency of which spring is to bring the buttons and thereby the edges of the cuff together.

I do not intend to limit the invention to the details of the particular embodiment 100 described, as I am aware that modifications and changes may be made and I have therefore drawn the appended claims accordingly.

Furthermore the invention is adapted for 105 uses other than as a cuff-link.

I claim:

1. In a cuff link, a coupling sleeve, a pair of button members having overlapping parallel headed studs movable along one 110 another within said sleeve, each of said studs being movable outwardly substantially the length of the coupling sleeve whereby the separation afforded between the button members of the link is substantially twice the 115 length of the coupling sleeve.

2. In an article of the class described, a pair of button or head members, overlapping parallel headed studs carried by said members, said studs being movable outwardly along one another within a connecting or coupling sleeve and means co-operative with said studs for opposing outward movement thereof. 120

3. In an article of the class described, 125 a pair of button members having overlapping parallel headed studs, a coupling or connecting sleeve surrounding the headed ends of said overlapping studs, abutments at the opposite ends of said sleeve and 130

spring means between the headed ends of the studs and said abutments, said spring means permitting separation of the button members and tending to contract the distance therebetween upon such separation.

4. A cuff link comprising a coupling sleeve having separate compartments one overlying the other, overlapping studs having button members at their outer ends, 10 said studs extending into said overlying compartments and having headed inner ends movable therein, and coiled springs between said headed ends and end walls at the opposite ends of the compart-

ments, said coiled springs permitting separation of the button members of the links and tending to contract the distance therebetween upon such separation. 15

5. A cuff link comprising button members having overlapping studs movable 20 outwardly along one another, means for opposing outward movement of said studs, said means permitting separation of said button members.

In witness whereof, I hereunto subscribe 25 my name, this 26th day of March, A. D. 1921.

IRVING S. KAUFMAN.
